MULTIPLE RAM HYDRAULIC JACK

Otto Morgensen, Jr., Dayton, Ohio

Application August 3, 1940, Serial No. 350,634

5 Claims. (Cl. 60—52)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to hydraulic jacks and more particularly to jacks of this type having multiple rams for high lift use as in connection with aircraft maintenance.

In hydraulic jacks, it is necessary that provision be made for controlling the maximum fluid pressure as otherwise continued pumping of fluid to the jack would subject the jack to internal pressures far in excess of the stresses for which the jack structure was designed with resultant destruction of the jack. Also even if the pressures did not reach destructive magnitude, the continued pumping of fluid to create pressures in excess of that required to support the load is inefficient and enervating of personnel.

This problem has presented no difficulty for single ram jacks, as provision is made for the uncovering by the ram in the extended position of a port to a conduit connecting the cylinder to the supply chamber, thereby relieving against further increase in pressure. Multiple ram jacks do not readily lend themselves to such a simple solution. Prior to applicant's invention, resort was generally had to one of the following two solutions: (1) The provision of a pressure relief valve in the hydraulic line from the pump to the cylinders in which the rams were disposed. (2) The limiting of the quantity of fluid available to an amount not in excess of the volume of the cylinders and conduits when the rams are in the fully extended position.

However, these solutions have not been adequate in that if the relief valve were used, it was necessary to load the valve for a maximum pressure corresponding to the maximum load for which the jack is designed. Because of this inherent limitation, it is obvious that whenever the jacks are used with loads lesser than the maximum load for which it is designed, it is still possible and likely that the operator of the jack would consume unnecessary energy in pumping fluid into the jack under a greater pressure than that necessary to support the load since it would not be obvious when the extended position is reached. As a corollary of this defect, it will be obvious that if all the internal parts are subject to the maximum pressure for which the jack is designed, without reference to the load being lifted, the abutment restraining the piston of the

smallest ram must be made as rugged as the abutment for the largest ram.

Still another defect of this solution is that operating fluid would be lost through the relief valve whenever excessive pressures are applied unless the relief valve mechanism were so constructed, at additional cost and complication, so as to provide a return conduit to the fluid supply chamber. Whether or not the relief valve were provided with a return conduit to the supply chamber, it will be appreciated that if the jack were subjected to the maximum load for which it is designed and were supporting this load in a static condition, then, if an additional load were applied as would easily occur when used with aircraft as when the wind or additional loading might cause the center of gravity of the plane to shift to a position more closely to the jack, then fluid would be exhausted from the cylinders through the relief valve with each impulse of excessive load and the rams would settle correspondingly as the fluid is discharged.

On the other hand, the second solution heretofore used for limiting the maximum pressures to which the jack can be subjected is not effective for this purpose for the reason that the same pump that pumps oil will also pump air so that when the liquid in the supply chamber has been transferred to the cylinders, continued pumping results in the introduction of air into the cylinders. Likewise, if the liquid in the supply chamber were to become depleted for any reason to such an extent that there was an insufficient quantity to fully fill all the cylinders, air would then be pumped in the jack even before the fully extended position has been reached. The presence of air under compression in the cylinders containing the rams is objectionable for the reason that it produces a resiliency of "bounding" action of the rams, tending to make the position of the supported load unstable. Air must be removed before satisfactory operation can be obtained.

Therefore, it is the purpose of my invention to provide a novel means for limiting the hydraulic pressure to which the jack can be subjected in the fully extended position to an amount not in excess of the load. To do this, I have provided a buoyant operated check valve which is used in connection with the supply chamber so as to be effective to prevent the return of liquid to the supply chamber as long as it has liquid therein, but in contrast with the usual spring loaded or gravity actuated check valve, my novel valve does not prevent exhaust of air from the

pump through the valve when the supply chamber is empty. With the use of my novel check valve, the disadvantages pointed out above are overcome.

It is a further object of my invention to provide a novel means for automatically adjusting to the right amount, the quantity of fluid required by the jack.

It is still another object of my invention to provide as an integral part of such a jack, retractable casters which are urged into operative position for the jack with a force sufficient to support the jack per se, but which are retractable under slightly greater load so as to enable substantially all the lift load imposed upon the jack to be taken by the base of the jack.

It is yet another object of this invention to provide means for preventing the transmission of load through the piston to the jack structure in the maximum extended position of the jack, thereby permitting a reduction in weight of the materials used in its construction which would otherwise be required. This object is accomplished by my novel design in that the quantity of fluid that can be supplied to the cylinders is limited and therefore the rams cannot be extended beyond the position corresponding to the total liquid supply. Consequently, the retaining abutment for the smallest inner ram need not be made as strong as the rest of the parts, thereby resulting in the saving of precious weight. It will be obvious, however, that the upper end of the smallest cylinder should be constructed to act as a limiting means to prevent disassembly of the ram from the cylinder. These jacks being primarily designed for aircraft use, must often be transported in airplanes, and in fact are preferably carried as servicing equipment of each plane. Hence, the desirability of lightness and a high lift capacity per unit of weight.

Other objects and advantages of my invention will be apparent from the following description and accompanying drawings wherein like reference numerals indicate like parts throughout the several views.

Figure 1 is an elevation view of a jack embodying my invention.

Figure 2 is a section view taken on the line 2-2 of Figure 1 showing the hydraulic mechanism.

Figure 3 is a section view taken on the line 3-3 of Figure 2.

Figure 4 is a section view taken on the line 4-4 of Figure 3, showing the buoyant check valve in open position.

Figure 5 is a view similar to Figure 4 showing the check valve in closed position.

Figure 6 shows a modification providing a shield for the buoyant operated check valve.

Figure 7 is a section view taken on the line 7-7 of Figure 1.

Figures 8 and 9 are schematic drawings showing the operation of the check valve in the jack system.

Referring to the drawings, the jack, illustrated in collapsed position of the rams, will be seen to comprise a ground engaging base 10, base 12 for the hydraulic elements, detachably connected to the base 10 by means of stud bolts 14, an external sleeve 16 which is secured in the base 12 and forms the outer wall for the liquid supply chamber, and a pump 18 for providing the hydraulic pressure. Constructed in the base 10 are 3 housings 20 for receiving casters 22. The caster housings 20 may be angularly spaced with re-

spect to the center and each other in any convenient manner, or preferably as near 120° apart as the structure arrangement of the jack base 10 will permit.

The hydraulic mechanism is best illustrated in Figures 2 and 3, wherein the sleeve 16 which constitutes the outer wall of the liquid supply chamber 24, is seen to engage in liquid seal fit in a groove or recess 26 in the base 12. A sleeve 28 provided with screw threads at its lower end engages complementary threads 30 in the base 12. This sleeve constitutes the inner wall of the supply chamber and also serves as the cylinder for receiving piston 32. Piston 32 is formed with a central downward extending portion 34 having a central bore 36 therein and exterior threads 38. A gland nut 40, having a transverse slot 41 for engagement by a spanner wrench, secures a sealing element 42, of leather or other suitable material, to the outer face of the piston. Piston 32 is further provided with an upwardly extending skirt portion 44 which has interior threads for receiving the threaded lower end of sleeve 46 which serves as the piston rod or ram for piston 32 and also serves as the cylinder for piston 48 disposed therein. Similarly to piston 32, piston 48 is provided with a threaded downwardly extending central portion 50. To the lower face of piston 48 is secured a leather sealing element 52 by means of gland nut 54. It should be understood that the downwardly extending portion 50 is constructed with respect to the gland nut 54 so that the gland nut 54 rests on the inner face of piston 32 supporting the portion 50 in spaced relation to piston 32, for a purpose which will be explained hereinafter. Similarly to piston 32, piston 48 is also provided with an upwardly extending skirt portion 56 having interior threads for receiving the lower threaded end of the sleeve 58 which serves as the connecting rod or ram for piston 48.

Now proceeding to the top part of Figure 2, it will be seen that sleeve 28 is threaded at its upper end to engage a collar nut 60 having a recess 62 at its outer perimeter forming a support for the sleeve 16 and a recess 64 at its inner upper corner for receiving packing gland 66. Before securing nut 60 to sleeve 28, there is first assembled a strong washer-like annular plate 68 which serves as a lower support for the packing gland 66, and as an intermediate abutment for the skirt portion 44 of piston 32 when the piston has been forced to its upper extreme position. The upper end of sleeve 46 is likewise threaded to receive cap nut 70 which has an inner recess 72 for receiving packing gland 74. Just as in connection with nut 60, before assembling nut 70, a second washerlike annular plate 75 is first assembled for the purpose of a lower support for packing gland 74. It is desired to note in this connection that cap nut 70 does not need to be constructed as ruggedly or as strong as nut 60, since the hydraulic mechanism is so adjusted, as hereinafter described in the operation, that piston 48 will not transfer any hydraulic load to this cap nut in the extended position of piston 48. This nut and packing gland serve only to prevent leakage and prevent disassembly of inner ram 58. Sleeve 58 is interiorly threaded at its upper end to receive a collar nut 76 which is in turn interiorly threaded to receive an extensible load engaging member 78.

Liquid from the supply chamber is transferred to the head of piston 32 through conduit 80, conduit 82 and conduit 84, best seen in Figure 3. These conduits are formed, as illustrated, by bor-

ings made in base 12 and the open ends of the bores are then sealed by plugs 86, 88 and 90 respectively. Disposed in conduit 84 intermediate the pump 18 and the head of piston 32 is a conventional spring loaded check valve 92 for engaging a valve seat 94 to prevent return of fluid from the cylinder to the pump or to the supply chamber.

Intermediate conduit 80 and supply chamber 24 is my novel buoyant operated check valve 96. Referring to Figures 4 and 5, the buoyant check valve 96 is seen to comprise a nut 114 threaded into the chamber opening of conduit 80. The nut has a central bore 116 providing the connection between conduit 80 and supply chamber 24, and its lower end provides a seat 117 for the ball-check 118 which, in assembly, is first introduced into conduit 80 before the nut 114 is assembled. A float 119, made of cork or other buoyant composition, is disposed in reservoir 24 and connected to ball-check 118 by a slender wire 120. The float is held in fixed relation to ball-check 118 by means of bushing 121 having a flanged lower end 122 engaging the lower side of float 119 and having its upper end received in a washer 124 flush with the upper surface of the float. The washer, flange, and wire are then soldered together at 126. Adjustment of the distance between the float and ball-check is made by resoldering in a different position.

Intermediate the float and the nut 114 is disposed a baffle plate 128 spaced from the base 12 by spacers 130 and secured to the base by studs 132. The baffle plate has a central aperture 134 for receiving the wire 120. Secured to the baffle are upwardly projecting pin 136 which are adapted to be received in the registering bores of bushings in the float 119 so as to serve as guide pins for the float.

A needle valve 140 is provided to enable return of fluid from the cylinders to the supply chamber 24 through conduits 142 and 144 when it is desired to release the load supported by the jack or to return the pistons to a lower position.

Collar nut 60 has a threaded bore 146 for adjustably receiving threaded tube 148 which thereby provides a novel means for adjusting a predetermined liquid level in chamber 24. Tube 148 is fixedly secured by nut 150 and is provided with a cap 152 having an aperture 154 for providing access to the atmosphere. The tube 148 is effective to limit the level of liquid in chamber 24 to the position of its lower end, since the space in said chamber above the lower end of the tube has no vent, and therefore the trapped air prevents the filling of the chamber above this level.

The operation of the jack will best be understood with reference to the schematic showing in Figures 8 and 9 in collaboration with the showing in Figure 2. The chamber 24 is filled with liquid to a predetermined level corresponding to the volume of liquid required to substantially fill the conduits and piston cylinders when the pistons or rams are in the fully extended position. It is important to properly regulate this level, as otherwise, continued pumping after the rams have reached their fully extended position, results in the development of hydraulic pressures in excess of the load, and the transfer of the hydraulic forces to the cylinder caps or upper structure of the jack. Not only is such action deleterious to the jack, but it consumes needless time and energy of the operator. By means of my novel check valve in cooperation

with a quantity of liquid corresponding to the displacement volume of the piston cylinders and the volume of the conduits, I have provided means for preventing the transfer of hydraulic force to the upper cap nut 70 and yet avoided the objectionable features of a pressure relief valve jack system.

Observing Figure 8, the liquid in chamber 24 acts on the float 119 to cause same to lift the ball-check 118 into engagement with the seat 117. The piston 160 of pump 18 creates a suction in conduit 80 which enables the atmospheric pressure on the liquid in chamber 24 to force the liquid past the ball-check 118 in opposition to the buoyancy of float 119. Check valve 92 in the conduit 84 prevents the return of fluid from the cylinder containing piston 32 in response to the suction. Check valve 92 likewise prevents the return of fluid from this cylinder in response to the pressures created in the cylinder by the load. Then, on the force-stroke of pump piston 160, ball-check 118 prevents the return of liquid to supply chamber 24 and check valve 92 yields to permit the displacement of the additional liquid into the cylinder under the head of piston 32. This process will be repeated with continued operation of the pump until the liquid in the supply chamber 24 has been exhausted, as shown in Figure 9, at which time the float 119 will no longer urge the ball-check 118 into engagement with the seat 117. Now piston 160 on its suction stroke will take air into conduit 80 and lower the level of liquid in chamber 162, in the schematic drawing. In Figure 3, conduit 80 is shown made relatively large to provide a volume corresponding to that of chamber 162 in the schematic drawing. It is preferred that conduit 80, either itself or in connection with a reserve chamber, should provide a volume greater than the displacement volume of the pump for a purpose described hereinafter. On the force stroke of the pump, ball-check valve 118 being inoperative due to the absence of liquid in chamber 24 permits the exhaust of air from conduit 80 or chamber 162 through bore 116 into chamber 24. It will be appreciated that the air being exhausted through bore 116 by the action of the pump will have considerable velocity, and therefore will exert an aerodynamic pressure on float 119. The float being relatively light, will tend to rise under the pressure, urging the ball-check 118 into seating engagement, and thereby prevent the exhaust of air or fluid through the bore 116. If this were to occur, the desired objective of the float-controlled check valve would be defeated. Therefore, provision is made to deflect the air stream around float 119 and to avoid an aerodynamic pressure on the float, which is accomplished, as illustrated, by means of baffle plate 128 disposed intermediate the float and the bore 116. Not only does the baffle plate prevent the action of an aerodynamic force on float 119, but it also creates a back pressure in the path of the air stream through bore 116 so that there is created a favorable pressure differential on the seating face 164 of ball-check 118 tending to urge ball-check 118 away from the seat by aerostatic pressure. By keeping valve 96 open at all times when chamber 24 is empty, it will be noted that air is thereby prevented from passing through check valve 92 into the cylinders supporting the pistons.

Additional means of preventing the aerodynamic forces from closing ball-check 118 when liquid is absent from chamber 24, is shown in

Figure 6 wherein there is provided a conduit 80 a shield 170 enclosing ball-check 118 and having ports 172 in the side walls of said shield spaced so as to direct air being exhausted by the pump onto the convex seating surface 164 of the ball-check thereby removing any aerodynamic force from the bottom surface 176 of the ball-check and directing the aerodynamic force on the upper surface so as to urge the ball-check away from its seat 117. For purpose of assembly, the shield is preferably attached to nut 114 as by soldering or welding 178.

As above pointed out, conduit 80 is made sufficiently large to hold a volume at least equal to the displacement volume of pump 18 so that on the force-stroke of the pump, air only and no liquid will be forced through the bore 116. This is to prevent a spraying of liquid through this bore which might result in emulsification of the oil being used.

With further reference to the operation of the multiple rams, liquid is first introduced into the cylinder containing piston head 32 through conduit 84. When the piston has raised slightly, liquid also passes through bore 36 into contact with piston head 48. The gland nut 54 secured to piston head 48 has one or more diametrical slots 180 across the face thereof serving both to provide engagement for a spanner wrench and also to enable the liquid to flow into engagement with the entire head area of piston 48 to provide a sufficient pressure-area product so that the inner ram will operate under load. Downwardly extending portion 50 of piston 48 being spaced from the inner face of piston 32, cooperates with the slots 180 to accomplish this latter function.

Referring to Figure 7, the caster 22 is seen to be mounted on a shaft 190, slidably received in a bore 192 of housing 20. The caster is urged into engagement with the floor or ground by a spring 194 under a compression force slightly more than sufficient to support the weight of the jack. Cotter pin 196 prevents displacement of the shaft 190 from its housing when the jack is picked up off the floor or ground. It will thus be seen that if an appreciable load is placed upon the jack that the caster will retract within the housing 20 under the additional load, overcoming the compression force of the spring, and that substantially all of the load imposed upon the jack will be taken by the base 10 and not by the casters.

While my invention has been illustrated and described herein and is primarily useful in connection with multiple ram jacks, it is to be understood that my novel check valve and other novel features are not to be limited to such application or to the specific forms and modifications shown, but embrace such applications, variations and equivalents as are included in the appended claims.

I claim:

1. A hydraulic jack comprising a hydraulic cylinder, a piston in said cylinder, mechanical stop means associated with said piston and cylinder for delimiting the maximum piston displacement, a liquid supply reservoir having its upper end closed, a vertically disposed filler tube in said closed end, adjustable up or down to delimit the maximum volume of fluid which may be placed in the supply reservoir to a volume which is no greater than the said maximum piston displacement, a pump for transferring liquid from said reservoir to said cylinder, a check valve biased for one-way flow from said pump to said cylinder, a second check valve in the bottom of the

tank in the pump suction passage, a float in the supply reservoir attached to said second valve urged upwardly by the liquid in said reservoir to resiliently constrain said second check valve for one-way flow from the reservoir to the pump, and gravity-actuated means on said second valve to move said second valve to open two-way flow position when said reservoir is emptied of liquid and said float is thereby rendered ineffective.

5. The structure of claim 1 with a baffle plate associated with said second check valve and with said float so positioned that air returning to said reservoir through the opening of said second check valve may not raise said float to close said second check valve.

15. 3. In combination, a pump, a hydraulic fluid motor having a cylinder and an extensible piston therein, a closed reservoir for supplying fluid to said cylinder by means of said pump to extend said piston, means for limiting the extension of said piston in said cylinder, a valve intermediate the reservoir and the pump that is normally operative to prevent return of liquid to said reservoir but having means for establishing two-way communication between said pump and said reservoir when said reservoir is empty, and means for gauging the quantity of fluid which may be put into said reservoir so that it will not exceed the volume necessary to extend said piston to said limiting means, said gauging means comprising a tube extending through the top of said closed reservoir downwardly into said reservoir, with means to adjust said tube to vary the distance which it extends downwardly through said top.

25. 4. The combination with a hydraulic jack having a cylinder with a piston movable therein, of mechanical abutments to limit movements of said piston from a maximum retracted to a maximum extended position, thereby delimiting the maximum volume which may be pumped into said cylinder, a liquid supply reservoir, a measuring device associated with said reservoir adapted to so gauge the amount of liquid which may be put into said reservoir as not to exceed said volume which may be pumped into said cylinder, a pump arranged to move said liquid from said reservoir to said cylinder, and a suction valve for said pump having a float means which is associated 35 with the liquid in said reservoir to resiliently hold the suction valve closed and gravity means to hold said suction valve open when said liquid is all out of said reservoir and said float means is thereby made ineffective.

35. 5. In combination, a pump, a hydraulic fluid motor, a cylinder for said motor, a piston extensible in said cylinder, a closed reservoir for supplying fluid to said cylinder by means of said pump to extend said piston, a valve intermediate the reservoir and the pump that is normally operative to prevent return of liquid to said reservoir but having means for establishing two-way communication between said pump and said reservoir when said reservoir is emptied, and means 45 for gauging the quantity of fluid which may be put into said reservoir so that, when the entire volume is pumped from the reservoir into the cylinder the piston will not be extended thereby beyond a predetermined safe limit, said gauging means comprising a tube extending through the top of said closed reservoir downwardly into said reservoir, with means to adjust said tube to vary the distance which it projects downwardly through the said top.

OTTO MORGENSEN, Jr.
